UNITED STATES PATENT OFFICE

103,788

DESIGN FOR A DRESS ENSEMBLE

Margaret Michelson, New York, N. Y.

Application February 6, 1937, Serial No. 67,490

Term of patent 3½ years

To all whom it may concern:

Be it known that I, Margaret Michelson, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a rear view of the dress shown in Figure 1.

Figure 3 is an enlarged side view of the sleeve member of the dress shown in Figure 1.

The characteristic feature of my design resides in the wide reverred bolero jacket of the ensemble, said bolero having sleeves which form twin depressed puffs, as shown.

I claim:

The ornamental design for a dress ensemble, substantially as shown and described.

MARGARET MICHELSON.
